UNITED STATES PATENT OFFICE.

BENJAMIN E. WETHERBEE, OF SOUTH ASHBURNHAM, MASSACHUSETTS

IMPROVEMENT IN FOLDING CHAIRS.

Specification forming part of Letters Patent No. 179,242, dated June 27, 1876; application filed March 20, 1876.

To all whom it may concern:

Be it known that I, BENJAMIN E. WETHERBEE, of South Ashburnham, in the county of Worcester and State of Massachusetts, have invented certain new and useful Improvements in Folding Chairs, of which the following is a specification, reference being had to the accompanying drawings, forming a part of the same.

The nature of my invention consists in an improvement in that class of folding chairs in which the seat-frame and rear legs are rigidly united or constructed together, said improvement being in a device which forms a strong bracket attached to the seat-frame, a part of the hinge or pivot device for the union of the back-frame to the seat, and also a part of a toggle, which serves to unite the front legs and arms of the chair to the other parts.

Figure 1 is a side elevation of my invention. Fig. 2 is a side elevation of the same when folded up. Fig. 3 is a horizontal sectional view, showing the method of uniting the jointed parts.

In the drawings, A represents the back of the chair. This part is pivoted at C to the part B, which forms the arm and front leg of

the chair. A is also pivoted at its lower end, by the bolt E, to the part D, which forms the seat and rear legs of the chair. (See Figs. 1 and 2.)

K is a strong bracket-piece firmly attached, by a screw, H, to the part D. This bracket-piece K serves as a support for the bolt E, which unites the back-piece A with the seat-piece D. (See Fig. 3.) It (the bracket K) also serves as one arm of a toggle, the other arm of which is formed by the piece M, fastened by the pin or rivet L. The piece M serves to connect and hold the part B, which forms the arm and front leg of the chair, to the other part of the chair.

I claim as my invention—

In a folding chair, the combination of the back-piece A, the rear leg D, and the bracket and link-connection K M with the front leg B, all operating together as described, and for the purpose set forth.

BENJAMIN E. WETHERBEE.
